UNITED STATES PATENT OFFICE.

HENRY J. DANIEL, OF SUTHERLIN, VIRGINIA.

WATER CARRIER.

Application filed January 10, 1923. Serial No. 611,797.

To all whom it may concern:

Be it known that I, HENRY J. DANIEL, a citizen of the United States, and resident of Sutherlin, in the county of Pittsylvania 5 and State of Virginia, have invented certain new and useful Improvements in Water Carriers, of which the following is a specification.

This invention relates to carriers for 10 water and the like.

Briefly stated an important object of this invention is to provide simple and reliable means whereby water may be conveniently conveyed from a spring to a house or other 15 point of use without the necessity of going to the well or spring and manually filling the carriers.

A further object is to provide a monorail structure having convenient means whereby 20 the truck is held upon the rail at the end of its movement and when the buckets of water or the like have been removed.

A further object is to provide a monorail structure of the character specified which is 25 of highly simplified construction, durable in use and cheap to manufacture.

Other objects and advantages of the invention will be apparent during the course 30 of the following description.

In the accompanying drawings forming a part of this application and in which like numerals are employed to designate like parts throughout the same,

Figure 1 is a side elevation of the improved monorail structure.

Figure 2 is a fragmentary plan view of the improved monorail structure.

Figure 3 is a fragmentary perspective of the monorail structure, the view illustrating 40 the holding bracket for the truck when it reaches the limit of its movement in one direction and the view also illustrating the guide means for the rope by means of which the truck is moved upon the cable or track.

Figure 4 is a fragmentary perspective of the improved monorail structure, the view illustrating the means to fill the buckets with water.

In the drawing wherein for the purpose 50 of illustration is shown a preferred embodiment of the invention the numeral 10 designates a plurality of posts or standards which are driven into the ground a proper distance and which have their upper ends

tapered to an edge as illustrated in Figure 4. It might be stated that the upper ends of the posts 10 are grooved to partly receive a supporting cable or track 11 and a thin strip of iron or other metal 14 is secured to the beveled upper ends of the posts 10 and extends over the cable 11 so as to secure the cable in position. It will be observed that the metal 14 is comparatively thin so that the wheels of the truck may pass over the same without difficulty.

One end of the cable 11 is fastened to an anchoring post 15 having a bracing member 16 secured to a stake 18 which is driven into the ground.

The other end of the cable 11 is as illustrated in Figure 4 trained about and secured to a windlass 19 which in turn is supported by bearings 20 carried by a post 21. By turning the windlass 19 in the proper direction the cable 11 is tightened 75 and the windlass is provided adjacent one end with openings 22 for the reception of a tightening handle 23. When the cable 11 has been tightened the desired extent, the handle 23 is held in position by means of a prop or other suitable holding member 24. Of course when it is desired to further tighten the cable or to loosen the same, the member 24 may be removed.

The carriage or truck is designated by the numeral 26 and is provided at its ends with axles 27 which have connection with wheels 28. With reference to Figure 4 it will be observed that the truck 26 is of monorail type and the wheels 28 which are partially received in slots 29 in the truck operate upon the cable 11.

The intermediate portion of the truck 26 is provided with a U-shaped yoke 30 having a bight portion extending transversely of and rotatably secured to the top of the truck by means of staples 31 or other suitable fastening devices. The end portions of the yoke 30 are hooked as indicated at 34 and are adapted for supporting buckets or pails 36 into which water is discharged.

Attention is directed to the fact that the yoke 30 is rotatably connected to the truck so that in case a forward pull is suddenly exerted on the truck the buckets 36 will be moved rearwardly and the weight of the contents of the same will prevent the rear wheel of the truck from leaving the cable.

On the other hand when the truck reaches the limit of its movement at the upper end of the rail the buckets will swing rearwardly a limited extent and thereby hold what is now the rear wheel on the cable or track.

The truck is manually controlled by means of an operating cable or rope 39 connected at its ends to the ends of the truck 10 and having an intermediate portion trained about a drum or windlass 40, the said drum or windlass being provided with a handle 41 by means of which the same may be rotated for operating the truck upon the 15 track. The standards 10 are provided with laterally projecting rollers 44 over which the operating cable 39 is trained and suitable guide wires 45 are connected to the standards and cooperate with the rollers in 20 guiding the cable. It will be observed that the several ends of the cord or rope 39 are secured to the ends of the truck by depending brackets 50 so that when the several 25 guide members 44 and 45 are passed the same will offer no resistance to the movement of the truck.

The lower portion of the operating cable 39 is passed between rollers 56 secured to the sides of the standards by means of attaching devices 57. It will be seen that the cable 39 which controls the truck cannot slide off the rollers and interfere with the 30 operation of the carrier.

In case the source of supply is at a point 35 lower than the point of use or the end having the drum 40 one end of the cable is connected to the carriage or truck and the other end is trained about a drum 40 and is secured thereto. By this construction 40 when it is desired to draw the buckets of water up from the point of supply it is merely necessary to turn the drum 40 whereupon the truck will travel upon the supporting cable 11. On the other hand when it 45 is desired to return the buckets to the well or point of supply the drum is turned in the opposite direction at the proper speed and the truck will return by force of gravity.

50 In this case the operating cable 39 is trained between rollers 60 and 61, the roller 61 being mounted for vertical sliding movement upon a pin 62 so that as the cable is wound upon the drum the pulley or spools 55 61 will guide the rope.

Figure 3 illustrates that the rearmost post 10 is provided with a transverse socket or recess 67 which partially receives the supporting cable 39 and directly above the 60 cable 39 the post 10 is provided with a pair of holding arms 70 which engage opposite sides of the adjacent wheel 28 in the manner illustrated in Figure 1.

65 Figure 1 illustrates that when the carriage or truck reaches the uppermost post

10 one of the wheels 28 passes between the parallel arms 70 and the truck is thereby held against transverse tilting when one of the buckets 36 is detached.

In operation the drum 40 is rotated so 70 as to move the truck and the buckets 36 carried thereby to the discharge end 75 of a trough 76 which may extend from a spring or other point of supply. When it is desired to use the water in the buckets 36 the 75 drum is rotated in the proper direction and the truck will travel on the cable 11 until one of the wheels 28 enters the space between the arms 70. As previously stated when the truck 26 is suddenly brought to 80 a halt the buckets 36 will swing forwardly and thereby prevent the rear wheel of the truck from leaving the track. The same is true when the truck reaches the point of supply and is suddenly brought to a halt as 85 the buckets will swing forwardly and thereby prevent what is now the rear wheel from leaving the track. This advantage is even more important when the truck reaches the supply point as the truck is generally traveling at a considerable speed and when suddenly brought to a halt the buckets will swing forwardly and hold the rear wheel in position.

90 When the buckets are filled with water the truck may be returned and the buckets detached. The truck cannot tilt transversely when one of the buckets is detached as the arms 70 will engage opposite sides of the wheel and hold the truck in position. 95

100 With reference to the foregoing description taken in connection with the accompanying drawing it will be observed that a carrier constructed in accordance with this invention may be conveniently operated 105 for carrying water from a remote point and that the truck cannot be easily pulled from the track. The carrier needs practically no attention and is capable of operation on a level or hilly ground and with a minimum 110 of effort on the part of the operator.

115 It is to be understood that the form of the invention herewith shown and desired is to be taken merely as a preferred example of the same and that such minor changes in arrangement and construction of parts may be made as will remain within the spirit of the invention and the scope of what is claimed.

120 Having thus described the invention, what I claim is:—

1. A carrier of the character specified comprising a body, wheels carried thereby, a U-shaped yoke having a bight portion rotatably connected to the body and extending 125 transversely thereof, the terminal portions of the yoke being provided with weight supporting means, the weight carried by the terminal portions of said yoke being adapted to hold the wheels in position when the truck 130

40

reaches the limit of its movement in one direction.

45

2. A monorail truck of the character specified comprising a body, wheels arranged at the ends of the body, a U-shaped yoke having a bight portion rotatably secured to the intermediate portion of the body, the terminal portions of the yoke being provided with object supporting means, the objects carried by the terminal portions of said yoke being adapted to swing when the truck reaches the limit of its movement in one direction whereby to hold the wheels in position.

50

3. A truck of the class described comprising a body, a yoke rotatably connected to the intermediate portion of the body and depending therefrom, object supporting means carried by the yoke below the plane of the body, and wheels connected to the ends of the body and held in position by the object carried by the yoke.

55

4. An apparatus of the character specified comprising a body having its end portions formed with slots, wheels mounted in said slots, a U-shaped yoke rotatably connected to the intermediate portion of the body and having arms provided with object supporting means, and a supporting member for the wheels, the objects carried by the arms of said yoke being adapted to swing when the truck reaches the limit of its movement in one direction whereby to hold the rear wheel of the truck in position.

60

5. A carrier comprising a plurality of standards, a cable connected thereto, a pair of parallel arms connected to one of the standards, and a truck mounted on said cable and having wheels, one of which is engaged

65

by said arms whereby to hold the truck in position.

70

6. A carrier comprising a plurality of standards, a cable connected thereto, a pair of parallel arms connected to one of the cables, a truck having wheels mounted on said cable, one of which wheels being engaged by said arms whereby to hold the truck in position, and a yoke connected to the truck and having object supporting means.

7. A carrier comprising a plurality of standards a cable connected thereto, a pair of parallel arms connected to one of the standards, a truck mounted on said cable and having wheels, one of which is engaged by said arms whereby to hold the truck in position, a yoke connected to the truck and having object supporting means, an operating cable connected to said truck, and a drum for operating said second cable.

8. A carrier comprising a plurality of spaced standards, a cable mounted thereon, an attaching and tightening member having connection with one end of said cable, an anchoring post having connection with the other end of the cable, a pair of parallel arms connected to one of the standards, a truck mounted on said cable and having wheels, one of which is engaged by said arms whereby to hold the truck in position, a yoke swingingly connected to the truck and having a pair of depending arms adapted for connection with objects to be carried, an operating cable connected to said truck, and a drum for operating said operating cable.

HENRY J. DANIEL.
